UNITED STATES PATENT OFFICE.

GEORGE S. CASCADEN, OF PHOENIXVILLE, PENNSYLVANIA.

DESIGN FOR A CHECKREIN-HOOK.

SPECIFICATION forming part of Design No. 18,561, dated August 28, 1888.

Application filed March 14, 1888. Serial No. 267,186. Term of patent 14 years.

To all whom it may concern:

Be it known that I, GEORGE S. CASCADEN, a citizen of the United States, residing at Phoenixville, in the county of Chester and State of Pennsylvania, have invented a new and useful Design for Checkrein-Hooks, of which the following is a specification.

My invention relates to a design for checkrein hooks; and it consists in a novel form and configuration, which is hereinafter fully described in connection with the accompanying drawing, wherein the figure represents a side view of a checkrein-hook showing my design.

The design consists of an initial letter, represented in the drawing by the reference-letter *a*, and a column, *b*. An open-sided loop

or letter, as *G*, is shown, and it is mounted on the column, which represents the Ionic style of architecture.

Having thus described my invention, I claim as follows:

A design for checkrein hooks, consisting of an open-sided loop representing the letter *G* surmounting the Ionic column *b*, as described and shown.

In testimony that I claim the foregoing as my own I have hereto affixed my signature in presence of two witnesses.

GEO. S. CASCADEN.
